Des. 222,265
Patented Oct. 12, 1971

222,265

ELECTRONIC CALCULATING MACHINE

Katsuhiro Ishida and Yoshisaburo Yoshida, Osaka, Japan,
assignors to Sharp Kabushiki Kaisha, Osaka, Japan

Filed July 1, 1970, Ser. No. 23,778

Claims priority, application Japan Jan. 21, 1970

Term of patent 14 years

Int. Cl. D14—02

U.S. Cl. D26—5

Fig. 5

Fig. 6

Fig. 4

Fig. 7

FIG. 1 is a front perspective view of an electronic calculating machine showing our new design.

FIG. 2 is a plan view of the electronic calculating machine;

FIG. 3 is a front elevational view;

FIG. 4 is a right side elevational view;

FIG. 5 is a rear elevational view;

FIG. 6 is a bottom view; and

FIG. 7 is a sectional view taken along the lines 7-7 of FIG. 2.

We claim:

The ornamental design for an electronic calculating machine, as shown.
